UNITED STATES PATENT OFFICE.

EMANUEL AUFIERO, OF BROOKLYN, NEW YORK.

MECHANICAL HORN.

1,078,529.

Specification of Letters Patent. Patented Nov. 11, 1913.

Application filed February 28, 1913. Serial No. 751,297.

To all whom it may concern:

Be it known that I, EMANUEL AUFIERO, a citizen of the United States, residing at Brooklyn, in the county of Kings and State 5 of New York, have invented new and useful Improvements in Mechanical Horns, of which the following is a specification.

My invention relates to a warning apparatus for use on automobiles, motorcycles, 10 or other vehicles; and has for its main object a compact and simple construction.

In the accompanied drawing, Figure 1, is a partly sectional view of one embodiment 15 of my invention; Fig. 2, is a sectional side view of same.

Similar numbers refer to similar parts in the two views.

A main cylindrical casing 5, made preferably of sheet steel drawn to shape, is provided with a flange 6 at right angles thereto co-acting with a front plate 7, to which a resonator 8 may be secured, to clamp and to hold in place a steel diaphragm 9.

I find it very desirable to provide a flexible projection 10, riveted on the diaphragm near its center, so that it may bend when the power applied at its tip is greater than the elastic limit of the diaphragm; I find in practice that this arrangement eliminates 30 the frequent adjustments required in devices of this class. A frame carrying the diaphragm actuating mechanism is composed of two horizontal posts 14 and 14', held in alinement by a circular front plate 15, which

35 fits the casing 5, and is adapted to slide therein, and at the rear by a cross-member 13. A pinion 23, solid with the rotary shaft 23' is journaled on said posts; rigidly mounted on pinion 23 is the bar 25, carrying

40 a pawl 26, which drives a ratchet 27 fastened to a sleeve 31 loosely mounted on the pinion shaft 23': On sleeve 31 is loosely mounted the diaphragm actuating ratchet 24, and a spring box 35 is secured on one side of said 45 ratchet; the spring 36, one end of which is secured to the sleeve 31 is adapted to transmit power through the spring box to the diaphragm actuating ratchet.

It will be seen that while the pawl 26 is 50 driving the sleeve 31, the spring 36 will re-

silently transmit a rotary motion to the ratchet 24 which will set the diaphragm into rapid vibration.

A split ratchet 32, is removably secured at the opposite end of the sleeve 31, and a spring pawl 33 is adapted to engage said ratchet 32 and to prevent back motion of the sleeve when the pawl 26 returns to its normal position idly riding on the ratchet 27. The spring 33 is held in place by a 55 member 34 loosely mounted on post 14', so that the two portions of the spring 33, one which is in engagement with the ratchet 32, and the other portion which is longer than the portion which engages the ratchet abuts 60 against the shaft 18, may coact to produce the required elasticity for the shorter end thereof, an effect that would not have been secured if the longer end of the spring were 65 not flexible and did not coact with the 70 smaller end, through the rocking post 34.

A forward and backward motion can be imparted, by the operator, to the pinion 23 by means of a reciprocatory rack, or preferably by a toothed sector 18 mounted on 75 shaft 16, and adapted to be oscillated thereby. Hand or foot power may be applied to the sector by means of a handle 34', on the outer side of the casing 5, or by means of a cord 21 secured by means of a screw 22, 80 on a grooved sector 17 mounted on the shaft 16, and parallel to the sector 18. I find that with this arrangement, when the driver cannot use his hand power, he can operate on a foot lever which pulls the cord 21. 85

The rear part of the casing 5 is perforated at two sides leaving a cross-piece 12 carrying a screw 30, in engagement with the frame cross-piece 13, and co-acting therewith for adjusting the whole mechanism carrying 90 frame toward and from the diaphragm. Said screw 30 is formed of two portions having different threads, one smaller the other larger, so that one portion moves quicker than the other, such screw being 95 called differential in mechanics. The metal on the side of the cross-piece 12 may be bent inwardly as shown at 11, so that a guide is provided for the ends of the cross-piece 13 to fit and to slide therein. 100

2. An oval opening 38 is provided in the casing 5 for the shaft 16, which is moved back or forth in the adjustment of the device; the end of the cross bar 13 is provided with 5 an extension 38, through which the shaft 16 is adapted to pass, while said extension is adapted to close at all times the oval hole 38, so that the mechanism may be at all times inclosed from the weather.

10. Modifications may be made in the means provided in the casing itself for holding in place the cross-bars; and many other changes may be made in the device, as the elimination of the handle 34', and the securing of 15 the grooved sector 17, to which the cord is secured, at the place of the handle.

A pin 20 is fastened to post 14, and engages the inner sides of the oscillating sectors 17 and 18, acting as a stop therefor: the spring 20 19 is used to return the sectors to normal position.

By those skilled in the art many changes and substitutions may be made in the device without departing from the scope of 25 my claims.

What I claim is:

1. In a signaling apparatus of the class described, in combination, a diaphragm, a shaft, a sleeve loosely mounted on said shaft, 30 a diaphragm displacing member free to rotate at all times supported by said sleeve and adapted for independent rotary movement, resilient means connecting said sleeve and said displacing member, and oscillating 35 means actuated by the shaft and acting on the sleeve for the purpose described.

2. In a signaling apparatus of the class described, in combination, a diaphragm, a shaft adapted to be rotated backward and 40 forward, a sleeve loosely mounted on said shaft, a diaphragm actuating member free to rotate at all times supported by said sleeve and adapted for independent rotary movement, resilient means connecting said 45 sleeve and said actuating member, and means actuated by the backward and forward revolving shaft for imparting motion to the sleeve for the purpose described.

3. In a signaling apparatus of the class 50 described, in combination, a diaphragm, a rotary shaft, a sleeve loosely mounted on said shaft, a ratchet fixed to said sleeve, a diaphragm displacing member free to rotate at all times loosely mounted on said sleeve, 55 a resilient member connecting said sleeve and said displacing member, and means actuated by said rotary shaft acting on the ratchet to effect rotation of the sleeve for the purpose described.

6. 4. In a signaling apparatus of the class 60 described, in combination, a diaphragm, a shaft, a pinion fastened to said shaft, a driving sleeve loosely mounted on said shaft, a driving 65 ratchet secured to said sleeve, dia-

phragm actuating means free to rotate at 65 all times supported by said sleeve and adapted for independent rotary movement, a resilient member connecting said sleeve and said actuating means, a second shaft, a sector fastened thereto and engaging the pinion, an arm fastened to the last named 70 shaft and means operating on said arm for rotating the last named shaft and sector for the purpose described.

5. In a signaling device, the combination 75 of an elastic diaphragm, a shaft, a ratchet loosely mounted thereon, a toothed member free to rotate at all times for vibrating the diaphragm loosely mounted on the same shaft, a resilient element connecting said ratchet and said toothed member, and an oscillating pawl carried by said shaft for driving said ratchet in one direction only 80 for the purpose described.

6. In a signaling device, in combination, 85 an elastic diaphragm, a wear piece on said diaphragm, a shaft, a driven ratchet loosely mounted thereon, a toothed member free to rotate at all times contacting with the diaphragm wear piece and loosely supported 90 by the same shaft, a resilient element connecting said ratchet and said toothed member, an oscillating member carried by said shaft and actuated by the operator to drive said ratchet in one direction only, an automatic means for returning said oscillating member to normal position for the purpose 95 described.

7. In combination, an elastic diaphragm, 100 a rotatable shaft adapted to be moved forward and backward, an arm secured thereto and radially thereof, a pawl at the farther end of said arm, a ratchet loosely mounted on said shaft and driven by said pawl, a toothed member, free to rotate at 105 all times for vibrating the diaphragm and resilient means between said ratchet and toothed member for the purpose described.

8. In combination, an elastic diaphragm, 110 an impact piece on said diaphragm, a shaft, a ratchet loosely mounted thereon, a toothed member free to rotate at all times engaging the impact piece for vibrating the diaphragm loosely mounted on the same shaft, a resilient element connecting said ratchet 115 and said toothed member, an arm carried by said shaft, a pawl at the end of the arm engaging said ratchet, means actuated by the operator to move said arm and pawl in one direction only and automatic means to 120 return said arm and pawl to normal position, the pawl riding idly over the ratchet in its return movement.

9. In a signaling device, an elastic dia- 125 phragm, a shaft, pinion teeth formed at the end of the shaft, an arm fastened on part of said pinion, a pawl at the other end of said arm, a ratchet loosely mounted on said shaft

and engaged by said pawl, a toothed member free to rotate at all times for vibrating the diaphragm loosely supported by said shaft, a resilient member between said 6 ratchet and toothed member and an oscillating member actuated by the operator acting on said shaft through said pinion to drive said ratchet applying the power of

the operator to directly vibrate the diaphragm, whereby the toothed member is 10 adapted to continue its motion by inertia, after the removal of the operator power.

EMANUEL AUFIERO.
